CLAUS LEVINSEN, OF BROOKLYN, NEW YORK.

VALVE MECHANISM.

1,296,412.

Application filed November 12, 1918. Serial No. 262,118.

Patented Mar. 4, 1919.

To all whom it may concern:

Be it known that I, CLAUS LEVINSEN, a citizen of the Danish Monarchy, resident of Brooklyn, in the county of Kings and State of New York, have invented certain new and useful Improvements in Valve Mechanisms, of which the following is a specification.

This invention relates to improvements in steam valves and has particular relation to an improved valve construction for use in marine steam power plants for the purpose of automatically connecting the exhausts of the auxiliary engine units with the condenser or with the atmosphere according to whether the main power unit and its condenser are in operation or not in operation.

A valve of the type referred to is of advantage in that its use eliminates hand labor for the purpose of controlling the steam from the auxiliary when the main power unit ceases to operate and consequently it is a means tending to safety and economy in the operation of the power plant. Accordingly, my invention comprises a valve construction as hereinafter set forth and also in the combination of the valve with the main power units. In the accompanying drawing

Figure 1 is a sectional view of a valve embodying my invention; and

Fig. 2 is a diagrammatic view of a marine steam power plant equipped with my improved valve.

Referring to Fig. 1, the valve comprises a valve casing 3 forming a valve chamber 4 having a steam inlet 5 and two steam outlet ports 6 and 7 which lead to the outlets 8 and 9 respectively. The outlet 8 leads to the atmosphere and the outlet 9 leads to the main condenser.

The atmosphere outlet port 6 is controlled by a valve 10 which is seated by the spring 11 adjustable by a bolt 12 acting against a follower 13. The condenser outlet port 7 is controlled by a valve 14 which is kept closed by the spring 15 adjustable by a bolt 16 acting against a follower 17. The valves 10 and 14 are provided with guiding wings or members 18, 18 as will be understood. The spring 15 is adjusted to exert a greater pressure upon the valve 14 than the pressure of the spring 11 upon the valve 10.

Referring to Fig. 2 the numeral 19 denotes a marine steam engine connected in the usual manner to its condenser 20. 21, 21 denote the steam supply mains. 22 and 23 indicate

auxiliary power units. Thus 22 may represent a pump and 23 the generator unit for electric light and power. The number and arrangement of the auxiliary units are immaterial so far as this invention is concerned.

The auxiliary units are supplied with steam from the boiler (not shown) through the steam pipes 24, 24 controlled by valves 25, 25. The exhausts from each auxiliary unit is connected by pipes 27, 27 to the valve 3 and the latter is connected by a pipe 28 to the condenser and by a pipe 29 to the atmosphere. Valves 30 control the exhaust pipes 27.

The running of the main unit 19—20 causes high vacuum (or low pressure) on the condenser side of the valve 3, consequently the valve 14 will open under pressure of the exhaust steam from the auxiliary units, when one or more of these are in operation, and because of the suction from the condenser. The valve 10, will however, remain closed because of the atmospheric pressure thereon as well as the pressure of the spring 11.

When the main unit 19—20 ceases to operate, the pressure on the condenser side of the valve 3 will increase, consequently the valve 14 will be closed, while the valve 10 will be opened by the pressure of the exhaust steam from the auxiliary units through inlet 5, the steam will then pass out through port 6 and outlet 8 to the atmosphere and vice versa.

During this operation, it will be noticed, that if the spring pressures were equal, a portion of the exhaust steam from the auxiliary units would pass out to the condenser, but because the spring pressure on valve 14 is greater than on the valve 10, only the latter will be operated and the steam pass to the atmosphere.

When the main unit again starts to operate, the pressure is again reduced on the condenser side of the valve and the valve 14 will open, the valve 10 will close and the exhaust steam from 5 will again pass to the condenser.

It will be noted that the exhaust steam from the auxiliary units have a constant pressure to overcome in the valve chamber 4. To eliminate this objectionable feature I propose to connect a pipe 35 to the pipes 27, 27 at 36 and lead this pipe to the feed water heater 37. From the latter a pipe 38 leads

to another valve 3 which is connected to the condenser 20 by a pipe 39 and to the atmosphere by a pipe 40.

By this arrangement advantage is taken 5 of the exhaust steam in the chamber 4 to heat the feed water heater 37 from whence the steam then passes to either the condenser or the atmosphere, and the back pressure in the valve 3 is relieved.

10 I claim.

1. The combination with a main steam engine and its condenser, an auxiliary steam engine, of a valve mechanism comprising a casing provided with a steam inlet and two 15 outlets, said steam inlet being connected with the exhaust side of said auxiliary steam engine, one of the said outlets being connected to the atmosphere; the other of said 20 outlets being connected to the said condenser, valves for controlling the said two outlets and means for exerting a greater closing pressure on the valve which controls the outlet connected to the said condenser.

2. The combination with a main steam 25 engine and its condenser, an auxiliary steam engine and a feed water for said main engine, of a valve mechanism connected to the

exhaust of said auxiliary steam engine and the said condenser and communicating with the atmosphere, a similar valve mechanism 30 connected between the said feed water heater and the said condenser and communicating with the atmosphere and means in said first named valve mechanisms for automatically establishing communication between the said auxiliary steam engine and the said condenser when the main engine and its condenser are in operation, and for establishing communication between said auxiliary steam engine and the atmosphere 40 when said main engine and condenser are not in operation, and means in said second named valve mechanism for establishing communication between said feed water heater and the said condenser when the latter is operated and for establishing communication between said feed water heater and the atmosphere when said main engine and condenser are not in operation. 45

Signed at New York, in the county of 50 New York and State of New York this 6th day of Nov. A. D. 1918.

CLAUS LEVINSEN.
